CLAIM

The animal design for the children's desk/office accessory or tool/construction accessory, as shown and described.

DESCRIPTION

FIG. 1 is a top, right, front perspective view showing the animal design;

FIG. 2 is a front view showing the animal design;

FIG. 3 is a rear view showing the animal design;

FIG. 4 is a left side view showing the animal design;

FIG. 5 is a right side view showing the animal design;

FIG. 6 is a top view showing the animal design; and,

FIG. 7 is a bottom view showing the animal design.

Where utilized, the broken lines show portions of the children's desk/office accessory or tool/construction accessory that form no part of the claimed design.
